UNITED STATES PATENT OFFICE.

CLAY O. KAHLE, OF BREMERTON, WASHINGTON.

GOLF BAG.

Application filed February 1, 1928. Serial No. 251,000.

This invention relates to a player's bag for golf clubs having pockets, or the like, for golf balls.

- With ball containers or pockets of golf bags in general use the balls are carried promiscuously such that a plurality of balls must be withdrawn in order to select one therefrom suitable for use in the game, the others being returned to the container.
- 10 To obviate such inconveniences and to provide means permitting an inspection of the balls within the container therefor and the withdrawal of a selected ball only is the main object of the present invention. A further 15 object of the invention is to provide a bag with a ball container wherein the balls are securely held and safeguarded against the accidental loss.

A further object of the invention is to provide a ball container wherein balls are most conveniently inserted and expeditiously abstracted therefrom.

A further object of the invention is to provide a ball container embodying the above 25 advantages, which will be of simple and inexpensive construction and efficient in use.

The invention consists in the novel construction, adaptation and combination of devices hereinafter described and claimed.

- 30 In the accompanying drawing,—

Figure 1 is a rear elevation of a golf bag with an embodiment of the invention applied thereto, the inspecting and delivery opening of the ball container being illustrated in its 35 closed condition; Fig. 2 is a view of the bag, partly in side elevation and partly in vertical section, said section being taken substantially on broken line 2—2 of Fig. 1; Fig. 3 is a horizontal section on line 3—3 of Fig. 40 1; Fig. 4 is a section of the upper portion of the bag on line 4—4 of Fig. 2, with the upper portion of the ball container represented in its upwardly extending position; and Fig. 5 is a fragmentary rear elevation, to 45 a larger scale, of the bag with the ball inspecting and delivery opening illustrated in its open condition.

In said drawing, the reference numeral 10 represents a bag for golf clubs shown with 50 reinforcing bands 11 and 12 about the mouth 13 and lower end 14, respectively, of the bag, and with longitudinally disposed stiffening elements 15. 16 represents a handle and 17 is a shoulder strap both located at the back 55 of the bag and either of which may be utilized for carrying the bag.

The bag and other parts described above are for illustrative purposes and may be constructed of cloth, leather or other material.

According to the present invention, I provide a container 18 for golf balls, denoted by B, said container being of a general tubular shape of a transverse area exceeding that of a golf ball. Said container is disposed longitudinally of the bag, either inside or outside of the same. As shown, the container comprises a piece of flexible material 18¹ secured along its sides as by stitches 19 to the peripheral wall 20 of the bag whereby the portion of the bag material, as denoted by 20¹ in Figs. 1, 3 and 5, between the stitches 19 constitutes in effect a part of the peripheral wall of the container.

Above its connection with the bag, the material 18¹ of the container is formed of itself into a tubular shape which may be doubled upon itself to extend downwardly into the bag as shown in Fig. 2; or, it may be extended upwardly through the mouth of the bag as shown in Fig. 4.

The upper end 22 of the container is desirably open for the insertion of golf balls into the container; in which case such end may be fastened in a closed condition by the provision of buttons 23 or other suitable known fasteners.

The lower end 24 of the container is closed, but in proximity thereto the container 18 is provided in its peripheral wall with an opening through which the balls may be inspected and passed into and withdrawn from the container.

In applying the container interiorly of the bag, as represented in the drawing, said opening is provided in the bag structure proper and within the area 20¹ thereof.

More particularly, said opening, which is designated by 25, consists of a slot disposed in a plane longitudinally of the bag and parallel with the axis of the container 18.

Releasable fastening means is provided for securing together the bag material at opposite sides of said slot whereby the latter is retained in its closed condition and also, when the fastening means is disengaged, permitting the slot to be dilated to a relatively wide gap.

A fastening means well adapted for this purpose is of that type known as a separable garment fastener, an example of which is illustrated and described in U. S. Patent No. 1,219,881, issued March 20, 1917. In such a

fastener, is utilized two flexible stringer members 26 secured to the material of the bag or to the container at opposite sides of the slot and is adapted to be interlocked and unlocked 5 by means of a sliding cam device 27 mounted upon both members, the locking being effected by movement of the cam in one direction and unlocking by an opposite movement.

The device 27 is, furthermore, of the shape 10 of a capital letter Y with channels in the branches 27¹ for the respective members 26 whereby the members are caused to be spread apart in the downward slot distending movement of the device to provide a gap, as shown 15 in Fig. 5, of a width equal to or greater than the diameter of a ball B. In the upward movement of the device the latter serves to bring the members together and into locking relation with each other.

20 As shown in the drawing, said device is provided with a link 28 whereby the device is manually shifted in its unlocking and locking movements. Said link also serves as a catch over a staple attachment 29 above the 25 slot whereby a padlock (not shown) engageable with the staple is capable of securing the device 27 in its member locking position.

30 and 31 represents tabs provided above and below the slot to serve as finger holds 30 to facilitate the operation of the device.

In practice, the balls B may be successively inserted through the opening in the top of the container when it is protruded, as represented in Fig. 4, above the top of the bag; or 35 the balls may be inserted through the slot into the lower portion of the container, when such slot is in its horizontally distended condition as shown in Fig. 5.

40 Inasmuch as the container 18 may be thus applied with balls into its lower end through the slot provided therat, the upper end of the container may be closed if desired, but it has been found convenient, and permits used or misshaped balls to be inserted through 45 the top of the container onto other balls within the container.

By opening the container slot, as shown in Fig. 5, a plurality of balls are exposed to view and a selected one of which may be 50 withdrawn by the player. The slot is brought into its closed condition and thus secured by the fastening means provided therefor, of the character illustrated or by an equivalent.

It is believed that the invention and the 55 manner of using the same will be understood from the above described embodiment.

What I claim, is,—

1. In a golf bag, a ball container disposed longitudinally of the bag and provided at

its upper end with a ball receiving opening, 60 said container being formed in part by a portion of the peripheral wall of the bag and in part by a piece of flexible material secured to said wall interiorly of the bag, said wall portion being provided longitudinally thereof with a slot in spaced relation with both ends of said container, and a separable fastener comprising interlocking members secured to the bag structure at opposite sides of said slot, and means adapted to coact with 65 said members for actuating the latter to distend said slot to a width through which balls may be extracted from the container.

2. In a golf bag, a ball container of a tubular form arranged longitudinally of the bag and disposed interiorly thereof, said container having an open upper end adapted to be extended through the mouth of the bag, said container having in proximity of its lower end a ball-discharging opening which extends through the peripheral wall of the bag, and means for closing said ball-discharging opening.

3. In a golf bag, a ball container of a tubular form arranged longitudinally of the bag 85 and with an inlet in the upper end thereof, said end being adapted to be protruded through the bag mouth, and a closable opening provided in the periphery of the container near its lower end through which balls may 90 be extracted, and a means associated with the structure of the container for closing said opening.

4. In a golf bag as defined in claim 3 wherein the closing means for the referred to opening is adapted to effect the distension of the 95 opening.

5. In a golf-bag, a ball container secured to the bag longitudinally thereof, said container having in its periphery in proximity of its lower end an opening through which balls within the container may be inspected and extracted selectively, and a means for closing 100 said opening to prevent the accidental passage of a ball therethrough.

6. A golf club bag having interiorly thereof a longitudinally extending ball-containing pocket having an open upper end and an opening for the lower portion thereof through a lateral wall of the bag, and a movable closure for closing said opening, said opening being arranged so that balls contained in the pocket are exposed to view when the closure is opened to enable the balls being withdrawn selectively from the pocket.

Signed at Seattle, Washington, this 20th day of January, 1928.

CLAY O. KAHLE.
